UNITED STATES PATENT OFFICE

92,166

DESIGN FOR A TEXTILE TAPE OR SIMILAR ARTICLE

Vincent De Liso, Astoria, N. Y.

Application March 10, 1934, Serial No. 50,995

Term of patent 3½ years

To all whom it may concern:

Be it known that I, VINCENT DE LISO, a citizen of the United States, residing in Astoria, Long Island, in the county of Queens and State of New York, have invented a new, original, and ornamental Design for Textile Tape or Similar Article, of which the following is a specification, reference being had to the accompanying drawing, forming part thereof.

The figure is a face view of a piece of knitted textile tape of arbitrary length showing my new design.

The portion of the fabric represented by the central longitudinally extending continuous line contrasts in color from the rest of the tape.

I claim:

The ornamental design for a textile tape or similar article as shown and described.

VINCENT DE LISO.
